ATTORNEY

UNITED STATES PATENT OFFICE.

GEORGE JOHN UZMANN, OF BLOOMFIELD, NEW JERSEY.

TEXTILE COMB AND METHOD OF MAKING THE SAME.

Application filed May 18, 1925. Serial No. 31,178.

This invention relates to textile combs, or combs for use in the combing of raw silk, cotton and wool. More particularly the invention relates to the method whereby such combs are made.

The object of the invention is to devise a less expensive, more rapid and yet effective method of making such combs.

These combs comprise primarily a bar with one or more rows of needles protruding therefrom.

Heretofore it has been the practice of drilling the holes for the reception of the needles entirely through a solid steel or other metallic bar; the bar also being so machined as to form on the ends thereof specially shaped portions by which the comb may be secured in the machine of which it forms a part.

The drilling of a large number of very small holes through a comparatively thick piece of steel or metal bar is at best, rather difficult work, and results in the breaking of a great many drills. Also, it is common when using fine drills for drilling holes of any considerable depth in metal and especially in hard metal, such as steel, for the drill to turn and drill a slanting or curved hole.

According to my invention, instead of using a solid bar, I may use a hollow one, or in other words a tube. The holes are drilled or punched through the opposite sides of the tube; the needles inserted in the holes and the tube then filled with metal which serves to securely fasten the needles in position and at the same time make a solid and rigid bar. Separate end portions may then be attached to the bar for securing the comb in the machine in which it forms an integral or necessary part.

Referring to the drawings wherein I have shown what I now consider to be the preferred form of my invention:

Fig. 1 is a side view of a comb made in accordance with my invention.

Fig. 2 is a top view of the tube showing the holes for receiving the needles.

Fig. 3 is a sectional end view of the tube, with the needles in place and the tube filled with metal.

Fig. 4 is a modification.

In the drawings, 1 represents the tube; 2 the needles; 3 the holes in which the needles are placed and 4 the metal filling in the tube.

Referring to Fig. 3, the holes 3 may be either drilled or punched through the opposite sides 5 and 6 of the tube, in any desired number of rows; the holes on one side registering with the corresponding holes on the other side. The needles 2 are then placed in the holes in the position shown. The filling may then be poured into the tube 1 and permitted to cool and contract around the needles so as to grip them firmly and hold them securely in position.

Obviously, any suitable metal may be used for filling the tube, such for instance as lead, Babbitt metal or other suitable fillers.

Any suitable end portions 7 may be fixedly or removably attached to the tube 1, whereby the comb may be secured in the machine for operation.

It will be understood that the ends 7 which I have shown are only illustrative, and any other design of ends suitable for securing the comb in the combing apparatus may be employed. Also, if the ends are to be fixedly attached to the tube portion, soldering, welding or any other suitable method of accomplishing this may be employed.

While I have shown the bar portion of the comb as comprising a tube, it will, of course, be understood that any other suitable casing may be used, such for instance, as a channel bar 8 shown in Fig. 3. The holes 3 may be drilled in the opposite sides 5^a and 6^a of the channel bar as in the case of the tube 1.

Also, the needles may be secured in position in the tube, channel bar or other suitable holder by soldering, fusing, welding or any other desirable method. When so constructed, the filling of the tube or bar may be omitted.

In accordance with the provisions of the patent statutes, I have described my invention, together with the apparatus, which I now consider to represent the best embodiment thereof, but I desire to have it understood that the apparatus shown is only illustrative and that the invention can be carried out by other means. For instance, while I have shown the main frame of the comb as comprising, in the preferred form, a seamless steel tube of rectangular cross section, it is obvious that any other suitable frame may be used, and the invention extends to such variations.

Having described my invention, what I

claim and desire to secure by Letters Patent is:

1. In a textile comb, a hollow frame having holes in both the walls thereof, needles positioned in said holes, and a filling in said frame surrounding and engaging said needles, one end of said needles being free.
2. In a textile comb, a frame having oppositely disposed walls, both walls being provided with holes, needles positioned in said holes in both walls, and a filling interposed between said walls, one end of the needles being free.
3. In a textile comb, a frame having op-

positely disposed walls, said walls being provided with holes and needles positioned in said holes, said needles being secured to both of said walls, and having one end thereof unsupported.

4. In a textile comb, a hollow base member, a plurality of pins supported in said member, by the two walls thereof and by a filler contained within the member, the outer ends of said pins being of unequal lengths.

Signed at New York, in the county of New York and State of New York, this 16 day of May, A. D. 1925.

GEORGE JOHN UZMANN.
